UNITED STATES PATENT OFFICE.

FRANK H. COLBY, OF HAVERHILL, MASSACHUSETTS.

SASH-FASTENER.

1,334,737.

Specification of Letters Patent. Patented Mar. 23, 1920.

Application filed June 5, 1918. Serial No. 238,879.

To all whom it may concern:

Be it known that I, FRANK H. COLBY, a citizen of the United States, residing at Haverhill, county of Essex, Commonwealth 5 of Massachusetts, have invented certain new and useful Improvements in Sash-Fasteners, of which the following is a specification.

This invention relates to sash-fasteners adapted to frictionally engage a sash to prevent rattling thereof.

The object of my invention is to provide a simple and inexpensive device of this character which may be readily applied to a window sash and will, when adjusted, effectually eliminate the annoying rattle incidental thereto by taking up the looseness, as well as prevent the admission of air through the space between a loose sash and its casing by automatically correcting the slackness of fit.

My device may be applied to any sash in any position thereof, and in addition to its rattle-preventing and air-excluding features, assists to prevent the ready movement of the sash in any attempt to force an entrance.

These and certain other advantages which will appear more fully hereinafter, are secured in the device of the present invention, 30 the construction and operation of which is fully described in the specification which follows, illustrated in the accompanying drawings, and particularly pointed out in the appended claims.

Throughout the specification and drawings, like reference characters are correspondingly employed, and in the drawings:

Figure 1 is an elevation of a sufficient portion of a window sash and frame to illustrate the application and manner of use of my invention, and

Figs. 2, 3, 4 and 5 are detail views of one of the sash fasteners, removed.

I have indicated at A, a window-frame 45 of ordinary construction, and at B a sliding sash.

My sash-fastener is indicated at C, and consists of a substantially oblong revoluble button or catch substantially wedge-formed 50 in cross-section at one end to provide a friction locking surface C¹ adapted to be wedged between the sash and frame to take up all lost motion and looseness between the parts and to prevent the sash from rattling.

Preferably two fasteners C are employed, one at each side of the sash and at different

heights vertically thereof whereby to most effectively engage the frame A. Each fastener has a hole therein through which a brad or screw D set in the sash extends. 60

In order to facilitate turning the fastener on its pivot D into and out of engagement with the frame A, the fastener may have lateral wing portions C² extending above the plane of the wedge surface C¹, and preferably terminating short of said surface.

In applying my fasteners, the pivots D are driven or set into the sash at the proper places to dispose the fasteners C in effective relation to the frame A, care being taken 70 to so hang the fasteners as to present their thin edges C¹ toward each other. When properly hung on their pivots, the fasteners are swung upwardly by pressing upon their wing portions C² until their wedge-formed 75 surfaces C¹ enter between the sash and frame, being retained in such position by friction. In disengaging the fasteners they are simply swung in the reverse direction.

Various modifications in the form and construction of my device may obviously be resorted to, within the limits of the appended 80 claims.

What I therefore claim and desire to secure by Letters Patent is:

1. A pivoted sash fastener, consisting of a substantially flat oblong plate having its longitudinal edges raised above the plane of the plate to provide a pair of oppositely disposed spaced thumb operating portions, the opposite end of said plate being formed as a wedge surface extending continuously across the plate beyond the ends of said thumb operating portions, said wedge surface sloping downwardly from the end of one thumb portion to the adjacent corner of the plate and sloping upwardly from said corner back toward the thumb portion at the opposite longitudinal edge of the plate. 95

2. A pivoted sash fastener, consisting of a substantially flat oblong plate having its longitudinal edges raised above the plane of the plate to provide a pair of oppositely disposed spaced thumb operating portions beginning at points substantially opposite the center of the plate and terminating at one end of the plate, the opposite end of said plate being formed as a wedge surface extending continuously across the plate beyond the ends of said thumb operating portion, said wedge surface beginning at the end of one thumb portion and extending 100

105

110

downwardly to the adjacent corner of the plate, and said plate having a hole for a pivot between said thumb portions and in rear of the center of the plate, and a headed 5 pivot set through said hole with its head substantially flush with the upper faces of said thumb portions.

In testimony whereof I affix my signature in presence of two witnesses.

FRANK H. COLBY.
